Attorney.

UNITED STATES PATENT OFFICE.

ANSELM SCHMITT, OF BUFFALO, NEW YORK.

SMOOTHING AND SAD IRON HEATER.

SPECIFICATION forming part of Letters Patent No. 402,197, dated April 30, 1889.

Application filed February 8, 1889. Serial No. 299,145. (No model.)

To all whom it may concern:

Be it known that I, ANSELM SCHMITT, of Buffalo, in the county of Erie and State of New York, have invented certain new and useful Improvements on Laundry and Tailor Smoothing and Sad Iron Heaters; and I do hereby declare that the following description of my said invention, taken in connection with the accompanying sheet of drawings, forms a full, clear, and exact specification, which will enable others skilled in the art to which it appertains to make and use the same.

This invention has general reference to laundry and tailor stoves for heating sad and smoothing irons; and it consists, essentially, in the novel and peculiar combination of parts and details of construction, as hereinafter first fully set forth and described, and then pointed out in the claims.

In the drawings already mentioned, which serve to illustrate my said invention more fully, Figure 1 is a front elevation of my improved laundry and tailor's stove. Fig. 2 is a side elevation of the same, portions thereof being in section in line *x x* of Fig. 1. Fig. 3 is a sectional plan below the line *y y* of Figs. 1 and 2.

Like parts are designated by corresponding letters of reference in all the figures.

The object of my present invention is the production of an efficient stove for heating flat and smoothing irons for laundry and tailors' use. To accomplish this object I construct this stove essentially of a base, A, having the usual ash-pit for the reception of the ash-pan B, said base being provided with a door, C, having a sliding register, D, of the well-known construction to admit air to the sliding and rocking grate E, operated by the handle F, as clearly illustrated in the drawings. Above the base A is located the fire-pot G, lined in its interior with fire-bricks, H, while above the fire-pot there is the flaring middle piece, I, having a chute, J, provided with a suitable cover, *j*, through which chute coal is fed to the fire-pot G in an obvious manner. The flaring middle piece is covered by a plate, K, having in front and on both corners openings *k k'*, serving as passages for the hot gases of combustion from the fire-pot to the chimney, as hereinafter to be referred to. The plate K is provided on its under side

with ribs L to stiffen the same, and thereby prevent its deflecting or sagging when hot. Instead of ribs I may, however, use a series of pipes opening in front of the middle piece and terminating in bends L' in the rear, whereby a current of air may pass through said pipes, and thereby keep the same at a temperature low enough to prevent their bending, and thereby, furthermore, sustaining said plate K in a flat condition, which it would not be able to preserve were the plate unsupported, owing to the intense heat to which it is subjected. Upon the plate K, I locate a U-shaped top, M, having double walls, so as to produce therein spaces N N' N'', the two former being the side spaces and the latter an end duct, there being in the side spaces partitions O, producing ducts P P', which convey the gases of combustion passing through the openings *k k'* into the back or end duct, N'', from whence they escape through an opening, Q, in the outer rear wall of the top into the flue R, having on its top the stove-pipe S in the regular and well-known manner.

The front of the U-shaped top M is closed by a curved cover, T, hinged or otherwise attached to the top M at *m* in any desirable manner.

The irons to be heated are placed upon the top K and the door or cover T closed, when the said plate K will soon transmit heat to the irons and bring them to a serviceable condition.

To prevent this laundry-stove from emitting heat in the warmer seasons of the year, I first place into the interior of the fire-pot G between the iron thereof and the fire-brick an asbestos lining, I', which will intercept the heat rays and prevent them from reaching the outer iron shell of the fire-pot. In a like manner I shall line the sides of the top with asbestos sheeting, (not shown,) so that this heater may be readily used in the summer time without making its presence uncomfortably felt to the laundress or tailor.

The efficiency of this heater is attained by the peculiar construction of the plate K and the ducts in the top M, causing the heated gases to be concentrated below the said plate in the middle portion, I, and then to pass forward through the openings in said plate. In this manner the plate is always kept intensely

hot and in the best condition to transmit heat to the flat or smoothing irons placed upon the same.

In the inner back wall of the top M, I locate 5 a ventilator, U, to allow the hot air in the interior of said top to escape into the back flue, while in the said back flue I locate a further ventilator, V, to act as a damper and to regulate the draft of the fire.

10 To convert this heater into a stove for general heating purposes in addition to its pre-designed purpose, I remove the top M and substitute in place thereof one having no asbestos lining (such a stove being, in fact, shown in the 15 drawings,) but being otherwise constructed as described, so that all the plates and surfaces become radiators, and thereby attain the result desired.

Having thus fully described my invention, 20 I claim as new and desire to secure to me by Letters Patent of the United States—

1. As an improved article of manufacture, a laundry and tailor stove for heating flat and smoothing irons, consisting, essentially, of the 25 base having the grate, the fire-pot, the flaring

middle piece having the chute and cover, the plate having the side openings, and the top having the side and back flues, and the hinged cover, as and for the purpose set forth.

2. In heating-stoves, the combination, with 30 the flaring middle piece, of the plate and the series of tubes supporting said plate, said tubes having their exit in the back flue, as and for the object set forth.

3. In laundry and heating stoves, the combination, with a suitable base and fire-pot, of 35 a flaring middle piece, a plate having tubular supports and provided with passages in its forward corners, and a U-shaped top having double walls provided with ducts and a hinged 40 cover for said top, the whole being constructed and arranged in the manner as and for the purpose set forth.

In testimony that I claim the foregoing as my invention I have hereto set my hand in 45 the presence of two subscribing witnesses.

ANSELM SCHMITT.
